UNITED STATES PATENT OFFICE.

SAMUEL H. FLEMING, OF CLEVELAND, OHIO, ASSIGNOR TO NATIONAL CARBON COMPANY, OF CLEVELAND, OHIO, A CORPORATION OF NEW JERSEY.

ELECTRIC FURNACE.

1,192,050.

Specification of Letters Patent. Patented July 25, 1916.

Application filed January 7, 1914. Serial No. 810,720.

To all whom it may concern:

Be it known that I, SAMUEL H. FLEMING, a citizen of the United States, residing at Cleveland, in the county of Cuyahoga and 5 State of Ohio, have invented a certain new and useful Improvement in Electric Furnaces, of which the following is a full, clear, and exact description.

This invention relates to a continuous 10 electric furnace for heating granular material capable of giving off combustible gases.

The furnace is primarily intended to heat raw cokes to temperatures either below or above the graphitization point, though it is 15 equally capable of use in treating other materials.

In the electric calcination, or other treatment of coke, or other carbonaceous material, it frequently happens that the carbon 20 is heated to a much higher temperature at certain places than at others. Since carbon has a negative co-efficient of resistance, the current will be diverted from the cooler portions and concentrated in the path through 25 the material more highly heated. In this way, one portion of the material may rob the remainder of substantially all the current.

It is one object of my invention to converge the moving material toward the point 30 where the electric heat is applied so that it all must pass through a constricted area and be uniformly heated.

It has been impossible to calcine or other- 35 wise treat raw coke and coals, by sending the current through them, as such materials are substantially non-conducting to the electric current.

It is another object of my invention to 40 provide an arrangement and method whereby this can be readily done.

It is known that material can be heated 45 to moderately high temperatures more economically by gas than by the electric current, and in graphitizing carbon, or in calcining it to very high temperatures, it is more economical to first pre-heat the carbon by means of gas, or by burning part of it, and then to heat it by the electric current 50 to the higher desired temperature.

It is a further object of my invention to provide an arrangement whereby such pre-heating of the material can be advantageously carried out.

55 In electric furnaces for heating calcined

coke, it has been found that carbonaceous growths form on the electrode ends and obstruct the operation of the furnace. These growths are caused by deposits of carbon from the hydrocarbon gases given off from 60 the coke calcined in the electric heating region.

In my electric furnace, which has the advantages previously set forth, the arrangement is such that substantially no growths 65 of carbon accumulate on the electrode ends.

The objects of the invention have been chiefly set forth above, but other objects will appear in the appended description taken in connection with the drawings, in which: 70

Figure 1 is a vertical cross section through the center of the furnace. Fig. 2 is a top view of the furnace roof and flue for the removal of combustion gases. Fig. 3 is an elevation of the upper part of the furnace looking along the line B—B of Fig. 2. Fig. 4 is a top view of the arch with the flue for removing the combustion gases removed, so that certain portions of the furnace are brought in view. Fig. 5 is a horizontal cross 80 section taken on the line A—A of Fig. 1. Fig. 6 is a vertical cross section taken on the diagonal line B—B of Fig. 2.

Referring in detail to the drawings, the outer walls of the furnace designated by reference character 1, are built in the form of a vertical shaft of fire brick or other suitable heat insulating material. As shown in the drawings, the inclosing walls are in the form of a square though they may be circular or 85 of other form, as the shape is immaterial as far as the invention is concerned. The base of the furnace shaft consists of the floor 2 of suitable material, and the upper portion is covered by a removable arch 3 of refractory 90 material, held together by structural steel members 5 and 6.

As shown in Figs. 1 and 3, the arch has a cylindrical curvature, the ends being closed by brickwork 6 which rests upon the top 100 portion of the furnace walls. A flue 9 consisting of two spaced rings 7 and 8, and a cover plate 10 is built on top of the arch. The cover plate has a central opening 11 for admitting the upper electrode as well as for 105 feeding the furnace charge into the upper part of the furnace. The flue space 9 communicates with the stack 12 through which the combustion gases are removed.

The combustion gases are admitted to the 110

flue 9, through a plurality of openings 13 (Fig. 4) in the arch 3, which may be formed by omitting certain bricks directly beneath the flue. A plurality of larger openings 14 are similarly provided in the arch exterior to the flue. These latter openings are usually closed during the operation of the furnace, as shown in Fig. 4, but may be opened for the insertion of tools whenever it is desired to get at the interior of the upper part of the furnace without removing the entire arch.

The ring 8 is beveled as shown, to provide a hopper 15 for the material fed into the furnace, and this hopper may be filled through a pipe 16. An electrode 17, which is preferably tapered near the end, extends through the material in the hopper and the opening 18 formed in the center of the arch, the latter opening being sufficiently larger than the electrode to permit the charge to be fed around it into the top of the furnace.

A partition 19 shown as a crown in the drawing, separates the furnace heating region into two chambers 20 and 21, one being for the pre-heating of the material, and the other for its final heating by the electric current. The crown is illustrated as being dome shaped, which is preferred on account of strength, though it may be of other form without departing from the spirit of the invention. Since the body of the furnace as shown, is rectangular in cross section, the corners between the walls and the crown are filled with material such as fire brick 22, for example. (Fig. 6.)

The crown 19 has an opening 23 to permit the passage of the upper electrode 17. A trammel 24 serves to key the brickwork of the dome. The crown 19 has a plurality of openings 25, arranged substantially at an equal distance from the center of the furnace, near where it joins the furnace walls. In Fig. 1 the openings shown in cross section are filled with material, but for purposes of illustration, the remainder, although similarly filled, are not thus shown. Upwardly extending members 26 are placed in the four corners just outside the adjacent openings 25 to prevent the material from clogging the inner air opening 30.

Within each of the four walls 1, around the chamber 20, is a channel 28 for pre-heating air which is admitted to the chamber for the combustion of the gases. The air is drawn in at openings 29 near the corners of the furnace, as shown in Fig. 5, and passes into the combustion chamber 20 at four openings 30, after traversing the channels in the walls. To secure a more tortuous path, projections 31 and 32 extend into the air channel from the top and bottom respectively. The lower electrode may consist of a plurality of electrodes 33 which extend through the furnace walls. The elec-

trodes 33, of which four are shown, fit into a channel 34 which is preferably constructed of graphite, on account of its electrical conductivity, and high refractory properties. The electrode being circular in section, the ends are cut to a rectangular shape to more easily fit in with the graphite bricks or slabs of which the channel 34 is made. The treated material is removed at the base of the furnace by conveyer 35 after it has been cooled by the water pipes 34.

The operation of the furnace is as follows: The granular carbonaceous material coming through the pipe 16, is admitted to the chamber 20 through the annular passage 18, around the electrode 17. The furnace may be placed in initial operation by feeding the charge through the hopper until the crown 19 is covered by a cone of the material, the base of which is prevented from spreading beyond certain limits by the exterior walls 1 and the annular pieces 26, as shown in Fig. 5. When this cone of material has been formed, the lower chamber 21 will be filled by the charge falling through the openings 25 in the crown. This material, of course, will fill up the space between the channel 34 and the outer walls as well as the channel itself, until it assumes the form shown in Fig. 1. The material outside of the channel remains in the furnace. When the furnace is filled to this extent, no further material will fall through the hopper 15 and the charge will be at rest until the furnace is put in full operation by starting the conveyer 35.

The surface of the cone in chamber 20, as well as that of the inverted cone in chamber 21, will assume the angle of repose, that is, the angle of friction of granular coke on itself. With this condition of affairs, a slight addition of material at the top causes material to slide down the surface.

It is preferable to initially start the furnace with calcined coke, and when the electric current is sent through the material, it will become intensely hot in the region of the top part of the channel 34. Calcined coke, that is, coke calcined by means other than the electric current, still has considerable volatile matter, and this will be driven off by the intense heat and pass up through the interstices of the coke, through the openings 25, and will burn at the base of the upper cone on meeting the air in chamber 20. Then by withdrawing the charge at the base of the channel 34, and feeding in a constantly increasing proportion of raw coke, the upper cone will be soon raised to a high temperature, due to the volatile matter driven off from the raw coke, which is burned on meeting the air coming through the tortuous channel 28. As soon as the upper cone becomes heated sufficiently, the feeding of calcined coke is discontinued and

raw coke alone is fed into the hopper 15. By regulating the size of the air openings, part of the coke may be burned to assist in the pre-heating.

5 As the conveyer removes the treated material from the bottom of the channel 34, the raw coke will be slowly moved down around the upper cone in a thin surface layer where it is calcined, and preliminarily heated to 10 a temperature in the neighborhood of 1000 degrees or more by the combustion of the gases given off from it. By the time it reaches the base of the cone, it is thoroughly pre-heated and passes through the openings 15 25 in the crown 19. The moving layer of pre-heated coke then slowly moves along the interior surface of the hollow cone until it converges to the electrode 17, where it passes downward through the channel 34 after being raised to the desired heat by the electric current.

On briefly summarizing the operation, it will be seen that the conveyer 35 at the base of the channel, will remove the treated material and cause a thin stream to move slowly down the diverging conical surface of chamber 20, then along the converging conical surface in chamber 21, toward and past the electrode end, and finally down 30 through the channel 34. In this way, the combustible gases in the coke are burned along the surface of the upper cone by the addition of pre-heated air. Since the material moves slowly in a thin layer, it is raised 35 to a high temperature and is evenly heated by the time it reaches the openings in the crown. The combustible gases are therefore, substantially all driven off and consumed before the material passes through 40 the openings 25 in the crown. Since it is impossible to entirely drive off combustible gases by heat treatment, there is always a small quantity of gas given off from the coke at the electric heating region, but this 45 is not sufficient to deposit any material amount of carbon on the electrode, and as there is a slightly reducing atmosphere under the crown, there is slow consumption of the electrode. Since all of the material converges at the electrode end, and moves in a narrow path in the electric heating region, the material is very uniformly heated.

In this type of furnace the expense is not only reduced by the use of the cheaper raw coke, but also by the pre-heating due to the burning of combustible gases contained therein. It has been found that the pre-heating of the coke in my type of furnace itself reduces the cost of electrical energy 50 from 25 to 50%.

While I have disclosed a resistor type of furnace that embodies my invention, it is permissible to use other types, and there are also various changes that can be made 55 without departing from the spirit of the in-

vention. The invention is therefore, to be limited only by the appended claims.

Having described my invention what I claim is:

1. In electric furnaces, inclosing walls, a cover coöperating with the said walls to form an inclosure and having a central opening, a partition in the interior of the furnace dividing it into two chambers, said partition having a plurality of openings 75 near its junction point with the walls and a central opening in line with the opening in the cover, means for admitting air to the upper chamber, an electrode extending through the said central openings and a second electrode coöperating with the first electrode to produce electric heat beneath said partition.

2. In electric furnaces, inclosing walls, a cover coöperating with said walls to form an inclosure and having an opening for admitting a charge to be heated, a partition in the interior of the furnace dividing it into an upper and a lower chamber, said partition having a plurality of openings near its junction point with the walls to permit the passage of the charge from the upper to the lower chamber and gaseous products from the lower to the upper chamber, means for admitting air to the upper chamber, means 95 for removing the gaseous products from the upper chamber and means for introducing electric heat into said charge beneath the partition.

3. In electric furnaces, inclosing walls, a vertical electrode, a cover coöperating with said walls to form an inclosure and having an opening for admitting said electrode and a surrounding charge, a partition in the interior of the furnace charge supporting the entering charge and having an opening for the passage of the electrode therethrough and a plurality of openings for the passage of the charge and means for passing an electric current through the electrode 110 and the charge beneath said partition.

4. In electric furnaces, inclosing walls, a cover coöperating with said walls to form an inclosure and having an opening for admitting a charge, a partition in the interior of the furnace dividing it into an upper and a lower chamber and having openings for permitting the passage of the charge, an opening for admitting air to the upper chamber to burn the gaseous products 115 therein, and means surrounding said upper chamber to preheat the air.

5. The method of heating material capable of giving off combustible gases, which consists in sliding it in a thin layer down a slanting surface, introducing air to burn the gases given off from the material in said layer, whereby it is heated, moving the heated material from the base of said surface passing it to an electric heating region, 125 130

below the slanting surface and removing it after passing through said region.

6. The method of heating granular material which consists in causing it to slide as a thin layer making an angle with the horizontal equal to the angle of repose of said material, burning a combustible mixture in proximity to said layer whereby it is heated, passing it into an electric heating region, and removing it after passing through said region.

7. The method of heating granular material which consists in causing it to slide as a thin layer making an angle with the horizontal equal to the angle of repose of said material, burning a combustible mixture in proximity to said layer whereby it is heated, causing the material to slide in a reversed direction as a thin layer making an angle with the horizontal equal to the angle of repose of said material with an electric heating region, and removing it after passing through said region.

8. The method of heating material capable of giving off combustible gases, which consists in causing it to slide as a thin layer making an angle with the horizontal equal to the angle of repose of said material, introducing air to burn the gases given off from the material in said layer whereby it is heated, causing the material to slide in a reverse direction, as a thin layer, making an angle with the horizontal equal to the angle of repose of said material, into an electric heating region, and removing it after passing through said region.

9. The method of heating material capable of giving off combustible gases, which

consists in causing it to pass in a thin layer down a slanting surface, making an angle 40 with the horizontal equal to the angle of repose of said material, introducing air to burn the gases given off from the material in said layer, whereby it is heated, moving the heated material from the base of said 45 surface and passing it into an electric heating region below the slanting surface.

10. The method of heating material, capable of giving off combustible gases, which consists in passing it in thin layers down 50 diverging surfaces, introducing air to burn the gases given off from material in said layers whereby it is heated, moving the heated material from the bottom of said diverging surfaces and passing it down converging surfaces, and heating it by the electric current at or below the converging point.

11. The method of heating material, capable of giving off combustible gases which 60 consists in passing it in a thin layer down a conical surface, introducing air to burn the gases given off from the material in said layer, whereby it is heated, moving the heated material from the base of the cone, 65 and passing it down a converging conical surface, and heating it by the electric current at or below the apex of said converging surface.

In testimony whereof, I hereunto affix my 70 signature.

SAMUEL H. FLEMING.
